UNITED STATES PATENT OFFICE

RICHARD V. McKAY, OF DUBUQUE, IOWA

DESIGN FOR A BOTTLE

Application filed April 26, 1929. Serial No. 31,014. Term of patent 3½ years.

To all whom it may concern:

Be it known that I, RICHARD V. McKAY, a citizen of the United States, residing in Dubuque, in the county of Dubuque and State of Iowa, have invented a new, original, and ornamental Design for Bottles, of which the following is a specification, reference being had to the accompanying drawing, forming part thereof.

In the drawing Fig. 1 is a front view; Fig. 2 is a side view; and Fig. 3 is a plan view, showing my new design.

I claim:

The ornamental design for a bottle as shown.

RICHARD V. McKAY.
